UNITED STATES PATENT OFFICE.

JAMES F. SNEDIKER, OF PHILADELPHIA, PENNSYLVANIA, ASSIGNOR TO
JOHN C. LOVE, OF SAME PLACE.

SEWING-MACHINE ATTACHMENT.

SPECIFICATION forming part of Letters Patent No. 258,490, dated May 23, 1882.

Application filed August 29, 1878.

To all whom it may concern:

Be it known that I, JAMES F. SNEDIKER, of Philadelphia, Pennsylvania, have invented a new and useful Improvement in Sewing-Machine Attachments, of which the following is a specification.

My invention relates to an improvement in that class of sewing-machine attachments in which the needle has a lateral reciprocating motion imparted to it for the purpose of making lateral or zigzag stitching, working button-holes, &c., the object of my invention being to construct an attachment of this class of a simpler and more effective character than usual. This object I attain in the manner which I will now proceed to describe, reference being had to the accompanying drawings, in which—

Figure 1 is a perspective view of my attachment; Figs. 2, 3, 4, and 5, side views, partly in section, showing the moving parts of the device in different positions; and Fig. 6, a front view of the device.

A represents the head of an ordinary sewing-machine—a “Singer” machine, for instance—and B the needle-bar of the same, the latter being reciprocated vertically by the usual mechanism, which it has not been deemed necessary to show or describe.

To the lower end of the needle-bar is secured a block, D, grooved for the reception and lateral guidance of a slide, a, in the under side of which are formed openings for the reception and retention of one or more needles, x.

On the back of the slide a is formed a rib, 35 to a recess in which is adapted the wedge-shaped lower end of a lever, F, the latter being pivoted to a bearing, d, formed on or secured to the block D.

To the front of the head A is secured a plate, 40 J, to which is pivoted a lever, e, having three arms, i, i', and i'', the arms i' and i'' being at right angles, or thereabout, to the arm i. The arm i is wedge-shaped, and the arms i' and i'' have inclined upper sides, so that the top of 45 the lever e presents a blunt wedge-shaped surface, upon which acts, as described herein-after, a spring-stud, m, arranged to slide in a tubular projection, n, of the plate J.

The operation of the device is as follows: 50 When the parts are in the position shown in Fig. 2 the needle-bar has just commenced to rise. As the said bar rises the upper end of the lever F strikes the inner inclined face of the arm i of the lever e, and is thereby moved

inward, the lower end of the lever F thus imparting a lateral movement in a reverse direction to the needle-carrying slide a. This movement continues until the upper end of the lever F strikes the under side of the arm i' of the lever e, as shown in Fig. 3. The upward movement of the needle-bar still continuing, the result will be the turning of the lever e in the direction of the arrow until it assumes the position shown in Fig. 4—that is to say, with the apex of its wedge-like upper 60 surface slightly beyond the center of the spring-stud m. The needle-bar now descends, and as soon as the upper end of the lever F has cleared the lower end of the arm i of the lever e the action of the spring-stud m on the upper end 65 of said lever causes it to assume the position shown in Fig. 5, so that on the next upward movement of the needle-bar the outer inclined surface of the arm i will act on the upper end 70 of the lever F, and a lateral movement in a 75 direction contrary to that above described will be imparted to the needle-carrying slide a, while the reversal of the position of the lever e will be effected by the action of the upper end of the lever F upon the arm i' of the said 80 lever e.

The above-described device is simple and inexpensive, and can be readily applied to an ordinary machine without necessitating material change of the latter.

It is not absolutely essential that the construction shown and described should be adhered to in every case. For instance, the lever e might be acted on by different forms of springs and the slide a might have a rigid upwardly-projecting arm, upon which the arm i of the lever e might act to reciprocate the slide, and by which the arms i' and i'' of the lever might be acted upon in order to shift the position of said lever.

I claim as my invention—

A sewing-machine attachment in which a pivoted spring-lever, e, having three arms, as described, is combined with a needle-carrying slide and an arm or lever for acting on and being acted on by the said lever e, as set forth.

In testimony whereof I have signed my name to this specification in the presence of two subscribing witnesses.

JAS. F. SNEDIKER.
